UNITED STATES PATENT OFFICE

146,849

DESIGN FOR A RADIO CABINET OR THE LIKE

Frank C. Burton, Grand Rapids, Mich., assignor
to Bendix Aviation Corporation, South Bend,
Ind., a corporation of Delaware

Application March 29, 1946, Serial No. 128,090

Term of patent 3½ years

(Cl. D56—4)

To all whom it may concern:

Be it known that I, Frank C. Burton, a citizen of the United States, residing in city of Grand Rapids, in the county of Kent and State of Michigan, have invented a new, original, and ornamental Design for a Radio Cabinet or the like, of which the following is a specification, reference being had to the accompanying drawing, forming a part thereof.

In the drawings:

Figure 1 is a front perspective view of a radio cabinet or the like, showing my new design;

Figure 2 is a top plan view thereof; and

Figure 3 is a side elevational view thereof.

The characteristic features of my design reside in the portions shown by means of full lines in the drawing.

What is claimed is:

The ornamental design for a radio cabinet or the like, as shown and described.

FRANK C. BURTON.
